Specification for Design.

Patented Apr. 3, 1917.

Application filed July 24, 1915. Serial No. 41,793. Term of patent 7 years.

To all whom it may concern:

Be it known that I, LUCIEN B. MARTIN, a citizen of the United States, and a resident of Lancaster, county of Fairfield, and State of Ohio, have invented a new, original, and ornamental Design for a Lens for Motor-Car Lamps, of which the following is a specification, reference being had to the accompanying drawing, forming part thereof.

In said annexed drawing:

Figure 1 is a front elevation; Fig. 2 is a

rear elevation; and Fig. 3 is a side elevation of the lens.

I claim:

The ornamental design for a lens for motor car lamps, as shown.

Signed by me this 17th day of July, 1915.

LUCIEN B. MARTIN.
